(21) Appl. No.: **29/112,036**

CLAIM

(22) Filed: **Oct. 8, 1999**

The ornamental design for an eyelet setting tool shank end
for beehive construction, as shown and described.

(51) LOC (7) Cl. **08-05**

DESCRIPTION

(52) U.S. Cl. **D8/14; D8/86; D8/47**

FIG. 1 is a side elevation view of an eyelet setting tool shank
end for beehive construction showing my new design, the
dashed line showing indicating environment only and not
comprising part of the present design;

(58) Field of Search **D8/14, 82, 47,
D8/86; 81/488, 44; 7/170; 227/51, 54, 55,
76; 30/358**

FIG. 2 is an enlarged fragmented view thereof;

(56) References Cited

FIG. 3 is an enlarged end view as seen from the right in FIG.
2;

U.S. PATENT DOCUMENTS

FIG. 4 is an enlarged fragmented view thereof; and,
FIG. 5 is a side elevation view thereof; the dashed line
showing indicating operational environment not comprising
any part of the claimed design.
